UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

LAMP-SOCKET.

1,023,916.

Specification of Letters Patent.

Patented Apr. 23, 1912.

Application filed March 16, 1907. Serial No. 362,743.

To all whom it may concern:

Be it known that I, REUBEN B. BENJAMIN, a citizen of the United States, residing at Chicago, in the county of Cook and State 5 of Illinois, have invented new and useful Improvements in Lamp-Sockets, of which the following is a full, clear, concise, and exact description, reference being had to the accompanying drawing, forming a part of 10 this specification.

This invention relates to improvements in electric lamp sockets, the object of the invention being the provision of a socket adapted to receive an incandescent electric 15 lamp and to hold the same with its axis disposed at an angle to the support to which the socket is attached.

Another object of the invention is to provide a socket in which the supporting part 20 is secured directly to the body of the casing, instead of to the removable cap or cover, as heretofore. When the cap is provided with a threaded bushing by means of which the socket is secured to the conduit, as is common 25 in earlier constructions, great difficulty is experienced in providing means for locking the body of the shell and the cap together with sufficient strength to prevent the body of the socket from being accidentally 30 detached from the cap or working loose when subjected to vibration. The act of screwing a lamp into the socket or removing the same therefrom, with most of the earlier constructions, was liable to cause 35 the separation of the body of the socket from the cap. By attaching the bushing directly to the body portion of the inclosing shell of the socket, I am enabled to provide a socket in which no strain is brought 40 to bear on the parts which would tend to cause the separation of the lamp-carrying part of the socket from its support.

As is well known, an incandescent electric lamp does not distribute its light equally 45 in all directions. A much greater amount of light is projected from the lamp in a direction transverse the longitudinal axis of the lamp than in the direction of this axis. Hence, it often becomes desirable to 50 attach the lamp receptacle to a support such

as the arm of an electrolier, or to a wall bracket or the like, in such a manner that the lamp inserted into this receptacle will have its axis disposed horizontally, in order that the maximum amount of light obtainable from the lamp may be projected downward. This arrangement is especially effective when a parabolic shade is used over the lamp so as to cover one half of the lamp and throw the rays projected from 55 that side of the lamp downward.

In the drawings accompanying this specification, Figure 1 is a vertical sectional view of a lamp-receiving device embodying my invention, the section being taken on 60 the line 1-1 of Fig. 3, looking in the direction indicated by the arrows; Fig. 2 is a front elevational view of the same, looking into the lamp-receiving socket of the device; Fig. 3 is an elevational view of the 65 rear side of the device with the cover or cap removed therefrom and showing the means for connecting the leading-in wires; Fig. 4 shows the device in side elevation with the parts of the outer casing or housing 70 separated from each other, illustrating the method by which they are adapted to be secured together; and Fig. 5 is a broken 75 sectional view of a slightly modified form of the device adapted to permit conductors 80 to be led out through the casing to a portable lamp or switch.

In the several figures of the drawings, in which like reference numerals indicate the same parts throughout, 6 is a base, formed 85 of porcelain or similar insulating material, which carries the lamp-receiving socket and associated contacts, as well as the terminals for connection with the supply wires. On one side of this base is secured the lamp-receiving shell 7, this shell being held in place by screws 8 and 9 which extend through the base 6. The back of the base 6 is formed with a square depression 10 and a circular depression 11. In the square depression 10 is located a nut 12 into which the bolt 8 is 90 screwed. In the depression 11 is located a plate 13 into which the bolt 9 is screwed. This plate 13 is provided with a binding-screw 14 for the reception of one of the 100

leading-in wires, connection being thus made between the wire and the socket 7 through this screw 14, plate 13 and bolt 9. The edge of the base 6 is formed with a 5 notch 15, the rear face of the base 6 being formed with a channel 16 leading from this notch 15 to the depression 11. In this channel is laid the leading-in wire which is secured to the binding screw 14. The rear 10 face of the base 6 has also another circular depression 17, from which leads a channel 18 opening into the notch 15. A plate 19, provided with a binding screw 20, lies in the recess or depression 17 and conducts 15 current to the end of a bolt 21, this bolt extending centrally through the base 6 and forming the center contact of the lamp-receiving socket 7, a washer 22 being disposed under the head of the bolt 21, as usual. 20 This washer 22 and the head of the screw 21 are made to project from the base 6 by the annular projection 23 which is formed on this face of the base.

Surrounding and inclosing the base 6 is a 25 casing or shell 24 in the form of a cylindrical sleeve having one of its ends expanded to receive the base 6 and the rest of its body of slightly smaller diameter and inclosing the lamp-receiving socket 7. A sleeve 24^a, 30 of fiber or the like, insulates the socket from the casing. The shell 24 has, as an inseparable part thereof, either by being permanently attached thereto or formed integral therewith, an attaching device or support 35 part for attaching the socket to a suitable fixture. In the present instance, this attaching device consists of a neck 25 which is permanently secured to the shell 24 opposite the notch 15 in the base. The supply 40 wires are led in through this neck 25, the latter being interiorly screw-threaded so that it may be screwed onto the threaded end of a pipe or other support such as the arm of a wall fixture or electrolier. 26 is a 45 set screw adapted, when screwed in, to secure the device in place on such arm by preventing the rotation of the device and the consequent unscrewing of the same.

The rear side of the base 6 is inclosed by 50 a cap or cover 27 which in the particular form of device illustrated is adapted to be telescoped on over the shell 24, means being provided whereby, after this cover 27 is telescoped into place, it may be secured to 55 the shell 24 by giving to the same a simple twist or partial revolution. Such means consist of projections 28, 28 struck up by a punching process from the body of the shell 24, and corresponding depressions 29, 29 in 60 the cover 27 into which these projections extend when the parts of the housing are put together. To facilitate the putting on and removal of the cover 27, a channel or groove 30 is formed in the cap or cover 27, this

groove 30 leading from the edge of the cover 65 inwardly as far as the depression 29, but not opening directly thereinto. When the cover has been thrust onto the casing 24 as far as possible and is then given a slight turn, the projection 28 will move out of the 70 groove 30 into the depression 29, snapping into place and remaining in position therein. To remove the cover 27, considerable force must be applied to rotate the cover 27 backwardly and thus cause the projection 28 to 75 enter the groove 30, consequently it is impossible for the cover to become accidentally detached. This form of connection constitutes a sort of bayonet joint, but is superior to the ordinary bayonet joint, in that 80 it is provided with means for locking the rotatable part of the casing against rotation and consequent detachment of this part from the main body of the casing. Between the cover 27 and the back of the base 6 is 85 placed an insulating disk 27^a. It will be observed that the terminals of the contacts on the base are so located as to be accessible through the opening of the shell 24 which is normally closed by the cap or cover 27. 90 With this arrangement and by merely removing the cap or cover 27 access may be readily had to the binding screws of the terminals to tighten the same or to attach or detach the leading-in wires, or to make 95 repairs or adjustments, without disassembling the socket or detaching the same from the electrolier or other fixture by which it is supported in use. To prevent the base 6 from becoming turned in the casing 24, I 100 form the edge of the base with a pair of notches 31, 31 and indent in the material of the shell 24 a pair of inwardly-extending projections 32, 32 adapted to enter the notches 31, 31 in the base. 105

In the form of the device shown in Fig. 5, the cover 27 is provided with a central opening in which is inserted an insulating bushing 33. When it is desired to carry off from the device a pair of conductors leading 110 to a portable lamp, fan-motor, or the like, these conductors may enter through the opening 34 in the bushing 33, and will be secured to the binding-screws 14 and 20. Obviously, by making the proper connections, these conductors may extend to a switch in series with the lamp, so that the lamp may be lighted or extinguished from a distance.

Having thus described my invention, what 115 I claim as new and desire to secure by Letters Patent is:

The combination of a flattened base having a socket on one of its sides and recesses in its opposite side, binding-screws in said 120 recesses, contacts associated with said socket, connections extending through the base from said contacts to said binding-screws, a

housing for said base and socket, and means on said housing for making connection with a support or conduit for leading-in wires, said base having a notch adjacent said last 5 named means and channels extending from said notch into said recesses.

In witness whereof, I have hereunto sub-

scribed my name in the presence of two witnesses.

REUBEN B. BENJAMIN.
